UNITED STATES PATENT OFFICE

FRANK J. CAMPBELL, OF CHICAGO, ILLINOIS, ASSIGNOR OF ONE-HALF TO GEORGE W. BRIGGS, OF CHICAGO, ILLINOIS

BUTTONHOLE ATTACHMENT FOR SEWING MACHINES

Application filed March 25, 1925. Serial No. 18,091.

This invention relates to improvements in button-hole attachments for sewing machines, and has for one of its principal objects the provision of a simple, readily operated device which can be detachably connected with sewing machines of various makes for the rapid making of button-holes.

One of the important objects of this invention is the provision of a button-hole making device which shall be easy of operation, composed of a minimum of parts, and not likely to get out of order.

Still another and further important object of this invention is to provide, in a button-hole attachment for sewing machines, automatically operating feed means for the cloth, and, further, automatic means for shifting the stitch mechanism from one side to the other so as to form a double row of stitches, between which a slit may be cut, thereby forming a completed button-hole.

Other and further important objects of the invention will be apparent from the disclosures in the accompanying drawings and following specification.

The invention, in a preferred form, is illustrated in the drawings and hereinafter more fully described.

In the drawings:

30 Figure 1 is a front elevation of the improved button-hole attachment of this invention.

35 Figure 2 is a top plan view, a portion of the cover being broken away, and illustrating the device with the operating parts shown in the same position as in Figure 1.

40 Figure 3 is a top plan view similar to Figure 2, but with the operating elements depicted as in the act of shifting the line of stitch from one side of the proposed button-hole to the other.

45 Figure 4 is a view similar to Figures 2 and 3, and illustrating the various parts of the apparatus after the shift of the line of stitch has been accomplished, and showing the button-hole as almost completed.

Figure 5 is an end view, parts being broken away to show the interior construction.

50 Figure 6 is a perspective view illustrating

the construction and operation of the feed and stitch forming mechanism.

Figure 7 is a view similar to Figure 6, certain portions being removed and other parts being broken away to show the operation of the automatically reversing feed means.

Figure 8 is a perspective view illustrating the construction and co-operation of the means for shifting and reversing the line of stitch at one end of the button-hole.

Figure 9 is a perspective view illustrating the construction and operation of the means for shifting and reversing the lines of stitch at the other end of the button-hole.

Figure 10 is a perspective view illustrating more particularly the construction of the improved work feeding means.

Figure 11 is a perspective view, portions being omitted, showing the construction and operation of the oscillating stitch forming mechanism.

Figure 12 is a detail view illustrating the construction of the work-holding element.

Figure 13 is an enlarged perspective view showing a completed button-hole.

As shown in the drawings:

The reference numeral 10 indicates generally a casing in which the apparatus constituting the improved button-hole attachment of this invention is mounted, the casing being fitted with a bottom plate 11. As best illustrated in Figure 5, the rear upper portion of the casing 10 is rounded, as shown at 12, so as to provide a more compact and more readily constructed apparatus, and also to allow for the installation and efficient operation of the various adjustments and operating elements.

Pivotedly mounted adjacent one end of the casing 10 is an operating arm 14, having a slot 16 in the extending end thereof adapted for proper engagement with the clamping screw of the needle bar of an ordinary sewing machine. The connection between the needle bar and the operating arm 14 may be variably adjusted by shifting the connection in the slot 16, thereby readily accommodating the device to sewing machines having either long or short needle bar strokes. The operating

arm 14 is pivotally mounted on a rotatable shaft 18 and also mounted on this shaft adjacent the operating arm is a pair of ratchet wheels 20 and 22, as best illustrated in Figure 6.

5 The wheel 20 is fixed to the shaft 18 by means of a key or the like 24, as shown in Figure 7, the further end of the shaft 18 being formed with screw threads, as illustrated at 27. The ratchet wheel 22 is fixed to one end of a sleeve 26 rotatably mounted on the shaft 18, and of approximately one-third its length, and at the other end of the sleeve is affixed a stitch forming cam wheel 28 having a cam surface as shown. A cotter pin or the like 30 retains the sleeve 26 and its attached members in proper position on the shaft 18—27.

A pawl 32 is mounted in a suitable casing 34 on the operating arm 14 and is adapted to co-operate with the corresponding ratchet face of the wheel 22, whereby this wheel and the corresponding cam wheel 28 will be at all times rotated in the same direction, as indicated by the arrows in Figure 6.

Likewise mounted in the casing 34, and co-operating with the wheel 20, is a pair of spring-pressed feed pawls 36, adapted to selectively co-operate with suitable notches in the circumference of the wheel 20, so as to rotate the same and the attached shaft 18 and its screw-threaded portion 27 in either direction. As shown in Figure 7, either one of the pawls 36 can be held from feeding relation with the face of the wheel 20 by means of integral bent-over projections 38 and 39 in the edge of a plate element 40 positioned adjacent the wheel 20 and between it and the ratchet wheel 22. A pin 41 mounted in the member 14 prevents overthrow of the plate 40 and its pawl-lifting lugs 38 and 39. An integral outstanding arm 42 with a bent-over operating end 44 is provided on the plate 40, the bent-over end 44 being adapted to alternately co-operate with projections 46 and 48, respectively, forming part of an oscillating and longitudinally shiftable carriage 50, as best illustrated in Figure 9. The plate 40 and its integral arm 42—44 is regularly moved in unison with the needle bar member 14. This results from the frictional engagement of pawls 36 with the projections 38 and 39, and the engagement of pin 41 with these projections. While sewing along one side of the button-hole the relative position of plate 40 and lever 14, illustrated in Figure 7, is maintained, plate 40 oscillating with lever 14, being driven in one direction by the frictional contact between projection 38 and the upper pawl 36 and in the other direction by pin 41 engaging projection 39. At the end of the button-hole plate 40 is shifted relatively to lever 14 through arm 42 as later explained, whereby projection 39 is brought

lower pawl 36 and projections 38 is brought into contact with pin 41, and this relative position is maintained as lever 14 oscillates, throughout the sewing of the other side of the buttonhole, wheel 20 and shaft 18 now being intermittently rotated in the opposite direction. When the carriage 50 is in the position illustrated in Figure 4 the end 44 of the arm 42 will contact with the projection 48 and will continue to do so, thereby maintaining the stop 38 under the pawl 36 until such time as the carriage 50 is shifted to the left in the operation of the device when the next up and down movement of the arm 44 will cause it to contact with the lower edge of the projection 46, thereby turning the disc 40 with relation to the feed wheel 20 and allowing the stop member 39 to ride under its corresponding pawl 36. When the end 44 contacts with the projection 48 the lug 38 is maintained under the corresponding pawl 36, thereby allowing a work-feeding movement, as illustrated in Figures 4 and 7. As shown in Figure 2, this work-feeding movement is reversed when the arm 44 contacts with the member 46.

The carriage 50 is pivotally mounted on a rod 52, fitted in the casing 10, extending longitudinally therethrough, the carriage being oscillated on the rod 52 by means of the cam wheel 28, the edge of which operates in either one of two suitable bearing notches 51 and 53 in the carriage 50, the bearing notches being at all times maintained in contact with the face of the cam-wheel 28 by means of compression springs 54 (Figure 11). The carriage 50 is mounted for a very slight longitudinal movement on the rod 52 and is normally maintained in its left hand position as shown in Figure 9 by the spring 89. These compression springs 54 are maintained on suitable extending arms of a plate element 56, which is in turn pivotally mounted on a rod 55 in the lower end of the carriage 50, as shown, and the plate 56 is provided with an attached extension 57 extending outwardly under and connected with the cloth clamping mechanism so as to properly oscillate the same to form the stitches, as best illustrated in Figures 10 and 11.

Mounted on the screw-threaded portion 27 of the shaft 18 is a correspondingly screw-threaded element 60 having a pin 62 mounted in the top thereof, which pin 62 projects through a suitable slot in the top of the casing 10, whereby the member 60 is at all times maintained in an upright position and is thereby constrained to move in either direction upon corresponding rotation of the shaft 27. Adapted to co-operate with this element 60 are the upstanding forked ends 63 of a work feed plate 64, which extends downwardly over the stitch forming plate 58 and has its outer end bent over to form a casing or the like 66, in which is mounted a thumb-screw

68 adapted for suitable co-operation with a cloth clamping element 70. The forward end of this cloth clamping element is forked, as illustrated at 72, and attached to this forked end is a rectangular cloth retainer 74 having a suitable slot therein adapted for proper co-operation with the needle of the sewing machine, and which also retains the work in desired position. Plates 64 and 58 are fixedly secured together, the members 58 and 74 constituting the lower and upper portions respectively of a work clamp. The work clamp is fed lengthwise along the line of the button-hole by parts 60 and 64 (Figure 8) is shifted transversely of the button-hole after each needle penetration by parts 28, 50, and 56 to produce a zigzag stitch along the sides of the button-hole, and is shifted transversely of the original line of stitch at one end thereof by the operation of parts 60, 88, 50, 51, and 54, and at the other end thereof by parts 86, 63, 50, 89, and 53 in order to carry the seam from one side of the button-hole across the end to the other side.

25 Mounted on the forward edge of the bottom plate 11 of the machine is a manually adjustable element 76 whereby the length of the button-hole to be made can be determined. This element is L-shaped, as shown, and one 30 arm thereof has a slot 78 therein in which operates a thumb-screw 80. As shown in Figure 8, the arm 76 has downwardly turned edges which slidably co-operate with a corresponding rail 82, whereby the adjusting 35 plate 76 will be at all times maintained in proper relation with respect to the bottom 11 and with respect to its co-operating elements. An arm 84 extends inwardly from the member 76 and has its end bent over and in the 40 form of a cam 86, with which is adapted to co-operate one of the upstanding forked arms 63 of the work feed plate 64. When the upstanding forked end 63 rides inwardly over the cam face 86 the plate 64, together with the 45 attached work holding members 70, 72, 74, 58, 57, and 56 will be pulled inwardly, thereby shifting the line of stitch from one side of the button-hole to the other, and projecting upwardly and rearwardly from the carriage 50 is an integral arm 88 which is in position to contact with the member 60 at the 50 other end of its path of travel on the screw 27, and which, when such contact occurs, will be slightly displaced rearwardly against the tension of the spring 89, the beginning of this motion being indicated in Figure 3, thereby moving the relation of the cam wheel 28 from the notch 53 to the notch 51, as indicated in Figure 4, whereby the cloth holding mechanism 55 will be re-shifted to its original position, allowing the formation of a line of stitching on the opposite side of the button-hole. At the same time the operation of the feed wheel 20 is reversed, as the bent-over 60 extension 44 of the arm 42 is shifted upwardly 65

by coming into contact with the projection 48 (see Figures 7 and 9) on the next downward movement of the pivoted arm 14, thereby causing the extension 38 of the plate 40 to ride into position beneath the uppermost pawl 36 and allowing the lower pawl 36 to operate in the peripheral notches of the said wheel 20. Means is provided to prevent accidental displacement of the feed wheel 20 from its proper feeding motion, this means comprising a spring-pressed plunger 90, as best illustrated in Figure 5, having its end maintained in suitable contact with any one of the peripheral notches in the said wheel 20, by means of a leaf spring 92, and suitable adjustment for the position of the pin 90 is provided by means of screws 94 mounted in notches in the pin supporting plate 96 whereby the point of operation of the pin 90 may be varied to accommodate itself to different strokes of needle bars of particular machines to which the device of this invention is attached. A similar pin is provided for the feed wheel 22, as best shown in Figures 3 and 4.

25 It will be evident that herein is provided a button-hole making attachment which is simple of operation and entirely automatic in its movements, and which, moreover, can be readily adapted to be applied to practically any make of sewing machine now on the market, and which, on account of its simplicity of parts and minimum number thereof, is economical of manufacture and can therefore be produced in quantities so as to be distributed to the large number of owners of domestic sewing machines to whom button-hole making attachments have heretofore been inaccessible on account of their prohibitive expense.

30 The device can be attached to a sewing machine by removing the presser-foot of the machine and connecting the presser-foot bar to the lug 97 by the usual screw fitted into the opening 98. This method of attaching is made possible by the incorporation of an integral cloth clamping element into the attachment itself, as 70, 72, etc. The feed dog of the sewing machine operates in a slot 99 provided therefor in the bottom 11 of the attachment, this slot being indicated in dotted lines in Figures 2, 3, and 4.

35 I am aware that many changes may be made and numerous details of construction varied throughout a wide range without departing from the principles of this invention, and I therefore do not purpose limiting the patent granted hereon otherwise than as necessitated by the prior art.

40 I claim as my invention:

45 1. In a button-hole sewing attachment, the combination of feed means for the work, comprising a screw threaded shaft and means mounted on the shaft for oscillating the work to form stitches, said oscillating means including a sleeve rotatable on the shaft and

- a feed means and a cam wheel affixed to the sleeve, together with a longitudinally shiftable and transversely oscillatable carriage for supporting the work and means on the carriage for co-operating with the aforesaid cam wheel for forming stitches along two parallel lines in the work, and means for joining the lines of stitch at the ends of said parallel movement, said means including a manually adjustable cam for additionally regulating the length of the button-hole.
2. In a button-hole attachment for sewing machines, a reversible feed means, including a feed wheel, notches in the periphery of the wheel, a pair of selectively operated pawls mounted in co-operative relation with the wheel, and automatic means for disengaging one of said pawls from operative relation with the wheel, said means including a disc mounted adjacent the wheel, bent-over integral lugs on the disc adapted to ride under the end of either one of the pawls, and further means co-operating with the disc to automatically shift the same into position to allow either one of the said pawls to operate.
3. In a button-hole attachment for sewing machines, a pivoted feed arm adapted to be variably attached to the needle bar of a sewing machine, a notched feed wheel, and a ratcheted stitch forming wheel mounted adjacent the pivoted feed arm, pawls on the feed arm for operating said wheels, and means for preventing accidental reverse operation of the wheels, said means comprising a spring-pressed pin mounted adjacent the periphery of each of said wheels, and an adjustable support for the pins.
4. A device for making button-holes, including a reciprocating driving device, a screw driven thereby, a nut on the screw, work holding means connected to said nut, and shifting means operated by the nut for moving the work laterally at each end of its longitudinal motion, one of said shifting means comprising a manually adjustable cam.
5. A device for making button-holes, including a reciprocating driving device, a screw driven thereby, a nut on the screw, work holding means connected to said nut, and shifting means operated by the nut for moving the work laterally at each end of its longitudinal motion, one of said shifting means comprising a manually adjustable cam, and the other of said shifting means including a lug integral with the work oscillating and stitch forming means.

In testimony whereof I affix my signature.
FRANK J. CAMPBELL.
